SAFETY GOWN

Elizabeth H. H. Rogers, Toronto,
Ontario, Canada.Application June 1, 1946, Serial No. 673,793
In Canada March 29, 1946

1 Claim. (Cl. 2—114)

1

This invention relates to safety gowns for bed patients and particularly designed for infants to keep them covered and in a particular area of a bed, carriage or the like.

It is an object of the present invention to provide a simple safety gown which incorporates a sheet-like portion designed to act as a means for retaining the wearer in a predetermined position in a bed, carriage or the like.

A further object of the invention is to provide a gown of this character which will operate to prevent the wearer from becoming uncovered in the event that they should tend to toss or move to an abnormal degree.

A further object of the invention is to provide a gown of this kind which will operate to retain the wearer in a predetermined area of a bed, carriage or the like but which will also permit relatively free reasonable movement and, such as in the case of infants, free kicking movement or movement to one side or the other.

A further object of the invention is to provide a gown of this kind which will permit the user freely to sit up.

A still further object of the invention is to provide a gown of this character which is generally simple in construction and which may therefore be readily manufactured and made available at a reasonable cost.

With these and other objects in view the invention generally comprises a gown embodying a body portion including sleeves preferably designed to fasten at the back and extending substantially to the waist of the wearer, the remaining portion of the gown constituting a sheet-like element which may form a continuation of the front portion of the garment extending longitudinally and laterally therefrom in effect to form an apron acting as a covering for the lower limbs in the manner of a sheet or blanket capable of being tucked in under the mattress or otherwise secured to maintain the wearer in a predetermined area of the bed or carriage. The apron-like portion is partially overlapped around the back of the garment and secured in such overlapped way in manner to permit relatively free movement of the lower limbs and the reasonable movement of the body of the wearer.

The invention will be fully understood by reference to the following detailed specification taken in conjunction with the accompanying drawings.

In the drawings,

Figure 1 is a partially perspective view of a safety gown according to the present invention, looking at the gown from the rear.

2

Figure 2 is a schematic front elevation of the gown, and

Figure 3 is a perspective view of a child's bed to illustrate the mode of use of the gown.

5 Referring to the drawings, 10 indicates the body of the gown which is preferably designed to be secured along the back as indicated generally by the numeral 11. The gown is formed with sleeves 12 in the usual manner and constitutes 10 a normal gown from the shoulders substantially to the waist. The gown includes an auxiliary sheet-like covering portion 13 which may, for the purpose of description, be termed an apron portion. This is designed to cover the lower limbs and 15 form a means for retaining the wearer in a predetermined area of the bed, carriage or the like.

The apron 13 may form an integral part of the garment as it is cut out although it may also 20 be applied as a separate piece. Assuming the former construction for the purpose of the present illustration the pattern for the front of the gown is cut so that the sheet-like portion or apron 13 extends laterally on each side of it and is of 25 a substantial length. This forms the marginal side portions 14 generally defined by the upper free edges 15. The back portion of the body may then be applied to the front portion to form the body 10 and the marginal side portions 14 30 are then folded to overlie a portion of the back of the body and are secured to the back of the body such as by a line of stitching or the like 16 along a portion of the upper edge 15. This in effect provides for a reasonable tuck 17 or large 35 pleat in each side of the apron 13.

When the wearer dons the body of the garment the apron may readily be tucked in under the mattress both at the sides and at the lower 40 end thereof such as shown in Figure 3. The wearer is therefore held in a predetermined area of the bed, carriage or the like and is therefore kept from becoming uncovered. However, by reason of the substantial tucks 17 produced by stitching the upper edges of the marginal sides of the apron to the back of the body as at 16 a fullness is permitted in the central portion of the apron which will permit a baby or the like free kicking movement. Moreover, it will also permit the wearer to turn rather freely onto one side or the other as the lapped portions of the apron are lapped in a way as shown in Figure 1 to permit this. Obviously, the gown will permit the wearer to sit up in a natural manner without hindrance. Accordingly, therefore, the garment assures that 45 the wearer will be safely located in a predeter- 55

mined position, thus to prevent uncovering or inadvertent dislodgment from the mattress, but at the same time it permits of a relatively free reasonable movement of the lower limbs and/or body.

The garment is particularly adaptable for babies designed to keep them from getting uncovered and particularly in the case of sickness where this is of vital importance, whereas it will also function safely to retain the baby against rolling from the bed or rolling towards the edge of the bed and turning over which will eliminate the possibility of injury or smothering caused by these factors. It thus functions as a safety gown to meet these various hazards.

It also operates to avoid frequent changing of night clothes as well as substantial work in tending a baby. In this connection it will be obvious that since the gown is completely open at the back it does not tend to become so readily soiled as an ordinary nightgown, whereas in removing the baby from the bed, carriage or the like, it is only necessary to undo the fastening of the gown at the back and the baby can then readily be slipped from the gown. It can be readily returned and the gown slipped on again just as easily without disturbing the apron disposed in secure position.

The preferred form of gown embodies an apron which is designed to be tucked in over and under the edges of the mattress, but it will be apparent that an apron smaller in size might be applied and secured at the edges of the mattress by tapes or other means if this was desired.

While the gown is particularly adapted for babies it may also be produced in a larger size

in the case of relatively helpless or extremely sick bed patients so that the advantages thereof can be applied in this field also.

What I claim as my invention is:

- 5 A safety gown comprising a body portion designed to cover the upper portion of the wearer, an apron portion on said gown forming a continuation of the front portion of the body and extending laterally outward on each side thereof, 10 the upper laterally extended portions of said apron being partially folded around the back portion of the body and sewn thereto in effect to form, in the apron portion between the front and back portions of the body, a large pleat on each side, said laterally extending portions of 15 the apron being designed to be secured adjacent to the edges of the mattress of a bed, carriage and the like to retain the wearer within a predetermined area of the latter, said pleated portions of the apron permitting free movement of the lower limbs of the body and partial turning of the body onto one side or the other.

ELIZABETH H. H. ROGERS.
